FIG. 1 is a front elevational view of an endometriosis warming/cooling pad of this design;

FIG. 2 is a top plan view thereof,

FIG. 3 is a right side elevational view thereof, the left side view is a mirror image;

FIG. 4 is a front elevational view of a second embodiment of the design of FIG. 1;

FIG. 5 is a front elevational view of a third embodiment of FIG. 1, the rear elevational view being a mirror image thereof. This view is also a rear elevational view of the design of FIG. 1;

FIG. 6 is a top plan view of FIG. 5;

FIG. 7 is a right side elevational view of FIG. 5; and,

FIG. 8 is a rear elevational view of FIG. 4.

The broken lines found in the Figures, represent stitching.
